United States Patent Office

Des. 224,196
Patented July 11, 1972

224,196

BOOKCASE

Ransom Reaves, 679 E. McKellar,
Memphis, Tenn. 38106

Filed June 1, 1970, Ser. No. 33,237

Term of patent 7 years

Int. Cl. D6—04

U.S. Cl. D6—148

FIG. 1

FIG. 2

FIG. 3

FIG. 4

FIG. 5

FIG. 1 is a front elevational view of a bookcase showing my new design.

FIG. 2 is a top plan view thereof.

FIG. 3 is a side elevational view thereof.

FIG. 4 is a bottom view thereof.

FIG. 5 is a fragmentary sectional view taken as on the line V—V of FIG. 3.

The back elevational view, not shown, is substantially the same as that shown in FIG. 1, and the side elevational view, not shown, is substantially like that shown in FIG. 3.

I claim:

The ornamental design for a bookcase, as shown and described.
